Attorney.

UNITED STATES PATENT OFFICE.

STEPHEN JANNUS, OF SAN CARLOS, ARIZONA TERRITORY.

DEVICE FOR ALTERING THE SHAPE OF HORSESHOES.

SPECIFICATION forming part of Letters Patent No. 691,385, dated January 21, 1902.

Application filed December 11, 1900. Serial No. 39,468. (No model.)

To all whom it may concern:

Be it known that I, STEPHEN JANNUS, a citizen of the United States of America, and a resident of San Carlos, Gila county, Territory of Arizona, (whose post-office address is San Carlos, Gila county, Territory of Arizona,) have invented certain new and useful Improvements in Devices for Altering the Shape of Horseshoes, of which the following is a specification.

My invention is a device for altering the shape of horseshoes.

Under many conditions it is exceedingly difficult to provide adequate means, such as a blacksmith's forge and anvil, for properly shaping "horseshoes," and under this term I include any kind of metal shoe which is nailed to the hoofs of animals for the purpose of protecting the hoofs and making it possible for the animals to travel with safety and comfort over such ground as they would not ordinarily choose. The difficulty of this provision is due to distance from transportation facilities, as in new and unsettled countries, where the difficulty of providing adequate means for farriery increases with its necessity. Ready-made horseshoes are a well-known article of commerce. In almost every case such shoes require to be bent in some direction to fit them to the animal's foot. My invention comprises a novel device for accomplishing this result without fire, forge, or anvil. It may also be noted that an anvil cannot be taken apart for transportation and is the most difficult single piece that could be carried on a pack-animal's back where railroads or even wagon-roads do not penetrate. With my invention, however, a device is produced in the form of an associated series or group of projections and depressions, of which there are several sizes of each, so that a cold ready-made shoe of the proper size can be placed between two of the projections or depressions or outside one of the projections, as the case may be, and there held by the hand and struck and driven downward by a blow or blows from a hammer. This will either spread or contract the heel of the shoe. If it is desired to spread its upper portion, the heels of the shoe are driven down until they rest firmly upon the bottoms of the depressions, when further blows upon the toe of the shoe must result in

expanding the upper portion thereof. Provisions for making short bends in the shoes are also made and for contracting the sides without affecting the heels. In fact, my invention provides for changing the shape of the shoe in almost any manner without heating it at all. There is also a part of the plate upon which the shoe may be laid and flattened should it become bent during the process of alteration. This device may be made in the form of a metallic plate of a size very convenient for transportation—as, for instance, twelve by fourteen inches—and it is preferably made of malleable iron as being the most economical material possessing the desired strength and toughness, although it may be for a combination of sufficient strength with extreme lightness made of the finest cast-steel, all that is required being that it be able to withstand the heavy pounding to which it would be subjected.

The advantages of the employment of my invention are numerous. It will be found of great value by every teamster traveling long distances between settled points and in all camps in the far West where horses are used and shod, and, furthermore, by every moving cavalry regiment in every country.

The reduction of weight and the increase of convenience produced by my device for altering the shape of horseshoes I consider of the utmost importance, and therefore claim the same broadly, referring to the appended description and the accompanying drawings, in which—

Figure 1 is a plan view of a metallic plate embodying my invention. Fig. 2 is a transverse sectional elevation on the line 2 2 of Fig. 1. Fig. 3 is a sectional elevation of an alternative construction, and Fig. 4 is a detailed view on the line 4 4 of Fig. 1.

As indicated in the drawings, which represent a desirable embodiment of my invention, A is a metal piece which may be made in different forms, but is shown as a rectangle. The thickness of the plate A must be such that it will withstand unlimited hammering and pounding. For such a plate twelve inches in width and fourteen inches in length will be found extremely convenient dimensions. All of the necessary contrivances for performing the work of altering

the shape of horseshoes must be grouped upon the said plate, and therefore for practical reasons I prefer the following arrangement.

5 In a line near what I have called the "front edge" *a* of the plate and upon the line 2 2 are formed a series of depressions B' B^2 B^3 B^4 B^5 B^6 , the depressions being separated by projections C' C^2 C^3 C^4 C^5 . The depressions 10 B' to B^6 are in the form of blunt wedges, widest at the top and tapering downward to square flat bottoms *b*. Correspondingly the projections C' C^2 C^3 C^4 C^5 , which intervene between the depressions B' B^2 B^3 B^4 B^5 B^6 , 15 have upwardly-sloping sides and flat tops. In the series as shown the projections become wider in succession, so as to render the device most simple of operation, although it will be obvious that the order might be 20 changed, if desired. The depressions are just wide enough to receive the thickest shoes to be used, and plates will be made for different standards, as required. The solid metal plate at the end *C* forms the outer wall of 25 the first depression, and the solid metal plate at C^6 forms the last outer wall, so that there is provided a series of depressions separated by projections of different widths. *D* is a horseshoe the heels of which are to be contracted. 30 This is accomplished by placing the ends of the heels within the adjacent two recesses which will just receive them, when by striking on top of the shoe the heels will be driven down into the recesses and 35 brought together by the converging side walls, as indicated in dotted lines. The extent to which the contraction is carried will depend entirely on the extent to which the heels are driven down, and if it is desired to contract 40 the heels and also to spread the upper or forward portion of the shoe then the shoe is driven down until the heels become firmly seated at the bottom of the recesses B' B^2 , when additional blows upon the toe of the shoe 45 will spread it laterally to the desired extent. The recesses are, it will be observed, at different distances, so that to contract the heels of a very wide shoe they would first be driven down into the recesses which were wide 50 enough apart to receive them and then into the next and the next until the desired contraction was attained. In order to spread the heels of a horseshoe, they are placed over the widest projection which will enter between 55 them. As indicated in Fig. 2, the inner edges of the heels of a horseshoe *E* have been placed over the projection C^5 . Now by driving upon this shoe it will be forced down into the depressions B^5 B^6 , and the heels separated by 60 driving the shoe down until the heels rest evenly and squarely upon the bottoms of said recesses. A second row of depressions and projections may be provided and are shown in Fig. 1, the depressions being B^7 B^8 B^9 B^{10} 65 and the projections C^7 C^8 C^9 . These are precisely like those already described, except that

they are farther apart for the handling of the very largest shoes. The depressions of course should be wide enough to receive the thickest horseshoe; but it is not desirable to have them any wider than necessary, since their parallel walls when not too far apart materially assist in preventing twisting of the shoe while being altered. An additional still larger depression B^{11} is indicated in the rear 70 of these described, and shown in detail in Fig. 4. This depression has a vertical wall at one end, and its bottom curves upwardly therefrom to the surface of the plate. This depression B^{11} is desirably of the same width as 75 the others and is intended for holding the heel portion of one limb of a horseshoe *F*, so that the shoe may be contracted by a blow in the direction of the arrow, although blows may be applied from other directions than 80 that of the arrow for the purpose of bending the shoe in various directions, as will be 85 readily understood.

Toward the rear portion of the plate and preferably close to one end is located an oblong boss or former *G*. This is preferably integral with the plate, is oblong in form, and extends upward from the plate a little higher than the thickness of a shoe. The horseshoe *g* is shown in position upon the former where 90 it is held at toe and heel, and by striking said shoe at either side the middle portions of the sides can be contracted with the greatest facility. Upon the right-hand forward corner is shown a flat depression *H*. (Best seen in Fig. 2.) This depression is about the depth of the thickest horseshoe, and its inner wall *h* is curved upon the ordinary line of the side of a shoe, a shoe *H'* being shown in position. By the use of this depression when it is desired to act upon one side of a shoe only it 95 may be laid therein, as shown, against the curved wall *h*, which will support that side of the shoe and prevent its distortion while 100 blows are being delivered against the opposite side. Other uses for this depression will suggest themselves. On the opposite corner of the plate *A* is formed a depression *I*, which is similar to the one just described, except that it is provided with an end piece *i* and a 105 shoulder *j*, extending therefrom, whereby the heel of a shoe can be so held as to admit of bending the central portion of the side of the limb of the shoe, so as to put a kink into it, if necessary, to conform to some particular 110 horse's foot.

It is not essential that my device for altering horseshoes consist absolutely of a metallic plate formed with depressions and extensions, because the projections may extend 115 above the plate, as in Fig. 3, instead of being formed in the body of it, as hereinbefore set forth. In Fig. 3 the body of the plate is indicated at *B*. The plate *B* is provided with one or more series of projections K' K^2 K^3 . 120 Each of these projections is formed with upwardly-converging side walls and a flat top,

and they range in size from small to large, so as to be wide enough to spread the heels of the largest horseshoe, and some of them small enough to be similarly employed with 5 the smallest shoe. Between the projections K' K² K³ are corresponding depressions L' L² L³, which form downwardly-converging side walls, terminating in flat bottoms, which give an ample solid seat for the heels of shoes, 10 which are driven down onto them. The use of this form is not different from that shown in Figs. 1, 2, and 4, the inversion of the parts being shown by way of illustration, and it will be understood that where it is preferred 15 to construct apparatus with the projections above the line of the plate instead of below the other features described will also be provided in similar relation.

Having specifically set forth a desirable 20 form of my invention and the construction and arrangement thereof, it will be apparent that minor changes and modifications may be made in view thereof and without the exercise of invention.

Having described my invention, what I 25 claim is—

1. A light block of metal for the purpose described having in its face a series of sets of depressions of differing dimensions whereby

horseshoes of varying sizes can be expanded 30 or contracted.

2. A light block of metal for the purpose described having in its face a series of sets of depressions of differing dimensions and having a recess or recesses adapted to receive one limb 35 of the shoe whereby horseshoes of varying sizes can be expanded or contracted.

3. A device for altering the shape of horseshoes comprising a metallic plate provided with a row or rows of associated projections 40 and depressions upon which horseshoes of varying sizes can be expanded or contracted, and an unobstructed flat surface adapted to sustain a shoe to be flattened.

4. A device for altering the shape of horseshoes comprising a metallic plate provided with a row or rows of associated projections and depressions along the front edge, a raised former at one end of the remaining surface of the plate and an unobstructed flat surface 50 upon which a shoe can be flattened.

Signed by me at New York, N. Y., this 28th day of November, 1900.

STEPHEN JANNUS.
